UNITED STATES PATENT OFFICE.

GEORGE CUSTER, OF MONROE, MICHIGAN.

IMPROVEMENT IN HORSESHOE-CALKS.

Specification forming part of Letters Patent No. **138,618**, dated May 6, 1873; application filed March 22, 1873.

To all whom it may concern:

Be it known that I, GEORGE CUSTER, of Monroe, in the county of Monroe and State of Michigan, have invented a new and valuable Improvement in Horseshoe-Calks; and I do hereby declare that the following is a full, clear, and exact description of the construction and operation of the same, reference being had to the annexed drawing making a part of this specification and to the letters and figures of reference marked thereon.

Figure 1 of the drawing is a representation of a front view of my horseshoe-calk. Fig. 2 is a side view of the same. Fig. 3 is a top view of the same.

This invention has relation to the construction of heel-calks, of steel, for horseshoes; and it consists in providing each calk with a welding-lug, raised centrally on its upper surface, said lug being pointed at its upper end, having parallel front and back faces, and having lateral notches in its edges at its base portion.

In the accompanying drawing, the letter *a* indicates the body of the calk, somewhat trapezoidal in form, or tapering from above downward. The upper surface is level or parallel with the bottom, and from its center extends

upward the welding-lug *b*, which is formed with parallel sides *c c*, the edges *d d* being inclined toward each other and meeting to form an angular extremity, *e*. The edges *d d* are each notched at the base, as at *z*, so that the lug will be held securely in the welding operation. The upper surface of the calk forms a level shoulder, *n*, surrounding the base of the lug *b*, which is designed to fit up against the body of the shoe in welding, bracing the calk against a strain in any direction.

What I claim as new, and desire to secure by Letters Patent, is—

The heel-calk described, consisting of the body *a* and the central angular welding-lug *b* having parallel sides, and inclined edges forming the angular upper end *e*, and notched at the base at *z*, said lug being surrounded by the level shoulder *n*, substantially as specified.

In testimony that I claim the above I have hereunto subscribed my name in the presence of two witnesses.

GEO. CUSTER.
